UNITED STATES PATENT OFFICE.

LOUIS EUGÈNE VIARD, OF BAR-SUR-SEINE, FRANCE.

INTERNAL-COMBUSTION ENGINE.

1,090,894.

Specification of Letters Patent. Patented Mar. 24, 1914.

Application filed February 8, 1912. Serial No. 675,283.

To all whom it may concern:

Be it known that I, LOUIS E. VIARD, a citizen of the Republic of France, residing at Bar-sur-Seine, in France, have invented certain new and useful Improvements in Internal-Combustion Engines, of which the following is a full, clear, and exact description.

This invention relates to two-cycle internal combustion engines wherein the piston is internally guided by a fixed member and externally by the cylinder, said piston being provided with an internal explosion chamber into which the combustible mixture is conducted after having been previously compressed in the upper part of the cylinder during the up-stroke of the piston.

The invention consists in the novel construction, arrangement and combination of parts as hereinafter fully described, illustrated in the drawing and pointed out specifically in the appended claims.

The drawing shows a vertical sectional view of my improved engine.

25 The engine comprises a crank-case *h*, having bearings *c*, in which is mounted the crank-shaft *W*.

g indicates a cylinder mounted above the crank-case, the upper end of the cylinder being closed by a head *f*. The hollow piston *p*, is arranged to reciprocate within the cylinder and is provided with piston rings *S*, and to the lower end of said piston is jointed the connecting rod *b*, by means of 30 wrist-pin *X* which is mounted in lateral extensions *w*, cast integral with the cylinder. Arranged within the piston is a hollow stationary member *q'* forming an abutment and provided at its lower end with a horizontal 35 flange *q* upon which seats the lower end of the cylinder, and said member *q'* being provided with vertical slots *q'* to permit of the reciprocation therein of the wrist-pin. The upper end of the member *q'* is provided 40 with rings *S'* to maintain a tight joint with the inner wall of the piston, and it is also provided with a baffle *V* at its upper end. The member *q'* is further provided with vertical slots *O* to permit oil splashed up 45 within the member *q'* to lubricate the inner wall of the piston. The abutment *q'* constitutes an internal guide for the piston in its reciprocations. The lower end of the cylinder is provided at diametrically opposite 50 points with offset portions forming channels or grooves *d*, within which reciprocate

the extensions *w* on the piston. The cylinder is provided at one side with three ports or openings *h*, *i*, *j*, the upper and lower ports *h*, *j*, being connected by a pipe *Z*. Slidingly arranged within the opening *j* is a cylindrical piece *t*, which is pressed inwardly by a weak spiral spring *t'* whereby the inner end of the piece *t* is pressed against the outer face of the piston. The bore of the piece *t*, is of a section equal to that of pipe *Z*. The central opening *i* is in communication with a carburetor (not shown) by means of a pipe *a*. The cylinder is provided on the side opposite the openings *h*, *i*, *j*, with a port *e*, for the exhaust of the burned gases. The piston is provided at diametrically opposite points with openings *l*, *m*, which, when the piston is at the limit of its upward stroke coincide respectively with the ports *j* and *e*.

The ignition device comprises a spark plug *b'* screwed into the head of the piston and connected with an isolated terminal *b'* screwed into the head *f*, of the cylinder by means of a very light, flexible spiral spring *c'*. In practice the plug *b'* is to be electrically connected with a suitable source of electric supply, as a battery or magneto.

The cooling of the engine may be effected by suitable water or air circulation.

In operation, we will assume that the piston is at the limit of its upward or power stroke. As the piston descends it creates a vacuum in the compression space *c'* in the cylinder above the piston and as the upper edge of the piston uncovers the port *i*, it draws in a charge of explosive mixture until said piston reaches the limit of its downward stroke, the latter position being that indicated in the drawing. Upon the upward stroke of the piston the port *i*, will be closed and the charge will be compressed within the space *c'* and pipe *Z* until the ports *l* and *m* coincide with ports *j* and *e*. At this moment the compressed charge enters the space within the piston above the abutment through ports *j*, *l*, and *m* and fills such space, the incoming charge being directed upwardly by the baffle *V* so as to thoroughly scavenge the said space of the burned gases remaining from the preceding explosion, which gases are driven out through the ports *m*, *e*. Upon the next down stroke of the piston the charge which now fills the space within the piston will be compressed between the piston head and the abutment *q'* until just at

about the end of said downstroke the spark will be produced at the plug b' , igniting the charge and driving the piston upward, which piston in such upward movement will 5 compress the new charge drawn in through port i on the previous downstroke of the piston. When during the upstroke of the piston the ports l, m , coincide with the ports j, e , the burned gases will be driven out 10 through ports m, e , by the compressed mixture admitted through ports j, l , as before described and the above-described cycle of operation is repeated.

What I claim is:

- 15 1. In an internal combustion engine of the character described, the combination with a cylinder provided with an exhaust port e , an admission port i , and two other ports h, j , arranged respectively above and below 20 the admission port, of a hollow piston arranged within the cylinder and provided with two ports l, m , which, when the piston is at the end of its upward stroke will coincide with the exhaust port and the port j , 25 respectively, and the port i , at the same time being covered by the piston, a connection between the ports h and j , a fixed abutment arranged within the piston and constituting an internal guide for the latter, a spark plug 30 carried by the head of the piston, a terminal carried by the head of the cylinder, and an electric connection between the said plug and terminal.
- 35 2. In an internal combustion engine of the character described, the combination with a cylinder provided with an exhaust port e , an admission port i , and two other ports h, j , arranged respectively above and below the admission port, of a hollow piston 40 arranged within the cylinder and provided with two ports l, m , which, when the piston

is at the end of its upward stroke will coincide with the exhaust port and the port j , respectively, and the port i at the same time being covered by the piston, a connection between the ports h and j , a fixed abutment arranged within the piston and constituting an internal guide for the latter, a spark plug carried by the head of the piston, a terminal carried by the head of the cylinder, 45 an electric connection between the spark plug and terminal, and a spring-pressed cylindrical member arranged within the port j , and bearing against the external wall of the piston.

3. In an internal combustion engine of the character described, the combination with a cylinder provided with an exhaust port e , an admission port i , and two other ports h, j , arranged respectively above and 60 below the admission port, of a hollow piston arranged within the cylinder and provided with two ports l, m , which, when the piston is at the end of its upward or power stroke will coincide respectively with the exhaust 65 port and the port j , and the port i , at the same time being covered by the piston, a connection between the ports h and j , a fixed abutment arranged within the piston and constituting an internal guide for the latter, 70 said abutment being provided with diametrically opposite slots, a wrist-pin having bearings in the piston and adapted to reciprocate in the said slots, and a connecting rod pivotally mounted on the wrist-pin.

In testimony whereof I affix my signature in presence of two witnesses.

LOUIS EUGÈNE VIARD.
